Correction in Design Letters Patent No.
43,693.

It is hereby certified that in Letters Patent No. 43,693, granted March 11, 1913, upon the application of James L. Erskine, of Upper Montclair, New Jersey, for a "Design for a Handle for Shaving-Brushes," an error appears in the printed specification requiring correction as follows: Second column, line 5, for the compound word "shaving-bushes" read *shaving-brushes*; and that the said Letters Patent should be read with this correction therein that the same may conform to the record of the case in the Patent Office.

Signed and sealed this 15th day of April, A. D., 1913.
